Frank Z. Ahl

BY *George W. Webster*
ATTORNEY

UNITED STATES PATENT OFFICE.

FRANK Z. AHL, OF SACRAMENTO, CALIFORNIA.

HOT-AIR FURNACE.

Application filed October 29, 1924. Serial No. 746,550.

To all whom it may concern:

Be it known that I, FRANK Z. AHL, a citizen of the United States, residing at Sacramento, county of Sacramento, State of California, have invented certain new and useful Improvements in Hot-Air Furnaces; and I do declare the following to be a full, clear, and exact description of the same, reference being had to the accompanying drawings, and to the characters of reference marked thereon, which form a part of this application.

This invention relates to improvements in heat furnaces of the natural draft hot air supplying type, and particularly to one using gas or similar fuel.

The principal object of my invention is to construct a furnace of this character so that a very large heated surface against which the air comes in contact will be provided in proportion to the size of the furnace and the amount of fuel consumed.

Another object is to arrange suitable air intake and outlet baffle or deflector means in such a manner that a large amount of the incoming air to be heated will first be deflected to pass adjacent the hottest surface of the furnace before passing out through the distributing pipes. At the same time the air circulating past the less heated surface will be prevented from too quickly escaping from the furnace, thereby insuring that such air will be well heated by the time it passes out from said furnace. Nevertheless the passage of the air from the intake to the outlet is not obstructed sufficiently to hinder the proper amount of draft from being created and automatically maintained with the operation of the furnace.

A further object is to provide simple means for preventing any moisture of condensation of gas in the discharge flue from draining back into the furnace itself.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of the furnace.

Fig. 2 is a sectional plan on the line 2—2 of Fig. 1.

Referring now more particularly to the characters of reference on the drawings, the numeral 1 denotes a cylindrical shell supported from the ground or floor and having on its upper end a frusto conical cap 2. Air outlets 3, from which distributing pipes lead to the various rooms to be heated, project from the sides of the cap, the top of which is concave in the form of an inverted cone, as at 4.

Mounted centrally in the shell and closed both at top and bottom is the main fire chamber 5, at the lower end of which is located an upwardly facing gas or other suitable burner 6, the necessary air for which is obtained from a passage 7 leading from said chamber 5 to the outside of the shell.

Surrounding the chamber 5 and concentric therewith is a drum 8 extending to the top of said chamber but terminating short of the bottom thereof and of the bottom of the shell. The inner periphery of this drum is spaced a suitable distance from the chamber to leave the air passage 9 open from the shell below the chamber to the cap 2 thereabove. Air from outside the shell is admitted to this passage through a side opening 10 therein below the chamber 5.

The outer periphery of the drum is deeply corrugated from top to bottom as shown at 11, thereby greatly increasing the surface area of this drum over what would be the case if the drum were plainly cylindrical. The bottoms of these corrugations are spaced a suitable distance from the inner periphery of the drum, while the outer edges thereof are similarly spaced from the shell.

The drum is closed at top and bottom except for passages 12 adjacent the top thereof leading from the top of the chamber 5, and an outlet 13 at the bottom of the drum on the side thereof opposite to the passages 12. This outlet 13 connects with a discharge pipe or flue 14 preferably placed between two adjacent corrugations 11 and extending to the top thereof. At this point said flue joins on to a horizontal portion 15 which passes through the shell, the lower side of this horizontal portion having a downward slant away from the flue 14, as shown at 16. Since this horizontal flue, away from the direct heat, is the portion in which condensation is most liable to form, it will be seen that owing to its downward slant any mois-

ture therein will run in a direction away from the flue 14 and not into the same.

Depending inwardly from the shell adjacent the lower end of the drum and at 5 a downward angle is an air deflecting ring 17 having a central opening concentric with the chamber 5. This causes air entering the shell through the side opening 10 to be deflected toward the center of the furnace, 10 and causes the majority of the air to pass up through the passage 9 between the highly heated surfaces of the drum and chamber. This air on passing up clear of the drum strikes the cone 4 and is deflected toward 15 the outlets 3.

Projecting inwardly from the shell 1 about the top of the drum is a horizontal deflecting ring 18, extending across the space 19 between the shell and the drum, and inwardly from said space extending upwardly substantially parallel to the sides of the cap 2, as shown at 20. This causes the air passing up between the shell and the drum to be somewhat retarded during such passage, insuring that the air will be well heated 25 and forcing the same toward the center of the cap before it can pass through the outlets 3. The two air streams passing up between the central chamber and the drum 30 and between the drum and shell respectively will thus be merged with each other in the cap before passing through the outlets, and the total volume of air in the distributing pipes connected to the outlets 3 will 35 therefore be of even heat throughout, and without any relatively cool currents.

The shell cap and outlets, although not so shown in the drawings, will of course be covered with asbestos or similar heat retaining means, as is customary in the industry.

As is customary in hot air furnaces, a water vessel 21, open at the top, is mounted in the shell 1 just above the intake flue 7 and extending across the air passage 19, to 45 keep the air moist. This vessel projects to the outside of the shell, so that it may be readily filled, the exterior portion being closed by a removable cover 22.

From the foregoing description it will be readily seen that I have produced such 50 a device as substantially fulfills the objects of the invention as set forth herein.

While this specification sets forth in detail the present and preferred construction 55 of the device, still in practice such deviations from such detail may be resorted to as do not form a departure from the spirit of the invention, as defined by the appended claims.

Having thus described my invention what 60 I claim as new and useful and desire to secure by Letters Patent is:

1. In a hot air furnace having a vertical shell, a drum therein spaced from the shell, air intake means below the drum whereby air may pass upwardly between the shell and drum, means for heating the drum, and a cap on the shell having openings in its sides; an air deflecting ring in the shell above the drum, said ring comprising a horizontal portion extending from the shell to a point inwardly of the outer periphery of the drum above but close to the latter, and a tapering portion extending upwardly and inwardly at an acute angle from the inner 75 end of said horizontal portion.

2. In a hot air furnace having a vertical shell, a drum therein spaced from the shell and provided with a central opening from end to end, air intake means below the drum whereby air may pass upwardly either through the central opening or between the drum and shell, means for heating the drum and a cap on the shell; air deflecting means in the shell below the drum but above the 85 air intake arranged to cause the majority of the air entering the intake to pass up through the central opening of the drum.

3. A structure as in claim 2 in which said deflecting means comprises a ring sloping 90 downwardly and rearwardly from the shell and terminating in a central opening aligned with the drum opening below the drum.

In testimony whereof I affix my signature.

FRANK Z. AHL.
